REVERSIBLE PLUG AND POURING SPOUT
FOR CONTAINERS

William F. Punte, Syracuse, N. Y., assignor to
Continental Can Company, Inc., New York,
N. Y., a corporation of New York

Application July 28, 1934, Serial No. 737,431

6 Claims. (CL. 221—11)

This invention is an improved reversible plug and pouring spout for a container.

One of the features of the present invention is the provision of a plug and pouring spout in which each of these members operates as a stiffener and grip for the other.

Another feature of the invention is the provision of such a structure, including a bail which forms an attachment and also a pivot about which the structure may be rotated for selectively presenting the plug and the pouring spout at the container aperture.

Other features of the invention will appear in the course of the following specification and 15 claims in conjunction with the accompanying drawing, in which:

Figure 1 is a top view of a container having a reversible plug and pouring spout according to the present invention disposed thereon.

Figure 2 is a side elevation of the plug and pouring spout, with portions of the container in section.

Figure 3 is a sectional view through the plug and pouring spout and container, with the parts 25 in a different position.

Figure 4 is a top view of a container, showing a modified form of employment of the reversible plug and pouring spout.

Figure 5 is a side elevation of the same, corresponding to Figure 2.

In the drawing, the container is illustrated as having a top T and a body wall structure B. The top closure wall T has means for providing a discharge opening which is illustratively shown as comprising a disk piece D having a substantially cylindrical friction closure wall 10, a peripheral flange 11 which is soldered to the wall T and thus made tight, and a bottom portion 12 which is delimited by the scoring 13 which weakens the disk so that the bottom may be perforated for the purpose of discharge through the opening thus formed.

A clip 15 provides a pivot member and is secured to the top wall T and receives a bail 16 which has its free ends passed through apertures in the sides of a spout member S at a point remote from the pouring lip 17 thereof, so that the ends of the bail and the apertures do not obstruct the free flow in the spout, nor permit a leakage or escape from the spout. The spout also includes a substantially cylindrical portion 18 which is constructed and arranged for frictional engagement (Figure 3) with the wall 10 when the spout is in position for discharge. It is

preferred to curl the end of the cylindrical portion 18 inwardly to provide a flange 19.

The plug or reclosure member is rigidly connected with the spout member. It comprises a plug portion having a closed bottom wall 20 and a substantially cylindrical wall 21 which is frictionally received by the wall 10 to establish the reclosure. The plug is illustrated as being in part closed at its other end by a rear, partly arched portion 23 of the spout member, so that this portion of the spout member reinforces and stiffens the plug, while the plug itself holds the spout member against a major distortion. In the illustrated form, this is accomplished by providing a flange 21a on the wall 21 and curling the edge of the portion 23 about the flange to form a bead 22 which extends for more than 180 degrees around the plug member; and preferably completing the union by soldering.

When the container is filled and marketed, the parts are as illustrated in Figure 1. The shape of the spout prevents accidental displacement thereof as its margin is flush with the top of the container and below the plane of the double seam (for example) which joins the top and body of the container, and it is held in proper alignment by the bail 16. When the contents of the container are to be discharged, the finger or tool is inserted in the portion 18 or beneath the bail ends, and the unit structure comprising the pouring spout member and the reclosure member is swung upwardly about the pivot connection at clip 15. A suitable tool is then pressed downward against the bottom 12 so that the same is pushed in by a rupture at the scoring 13. The assembly of pouring spout and plug is then brought down upon the container end again, after a rotation of the parts about the horizontal axis provided by the ends of the bail, so that the cylindrical wall 18 is received in the wall 10 (position of Figure 3, dotted lines in Figure 1) and the parts are ready for the pouring out of the contents of the container. When the desired quantity has been discharged with guidance by the spout lip 17, the container may be reclosed by employing the projecting portions of the spout S or of the plug as a lifting means to disengage the frictional pouring-seal which has been existing, and the unitary structure is swung upwardly under guidance of the bail 16 and reversed end 40 for end, and the reclosing plug brought down until its wall 21 frictionally engages the wall 10.

It will be noted that the pouring spout wall 18 and the shoulder on the plug under which a tool may be placed to pry are utilized as engagement 45

50 55

portions for lifting the plug from position, while the plug can be utilized for lifting the spout from position. Furthermore, the spout can be seated securely in position by pressing downward upon the closure plug and the closure plug may be seated by pressing downwardly upon the spout.

5 In the modified form shown in Figures 4 and 5, the shape of the pouring spout member and the plug reclosure member is essentially the same 10 as before, and the parts are combined into a unitary structure having mutual supporting and co-operating parts.

15 In the form of Figure 5, a modified form of initial seal is provided. In this case the wall 10 about the discharge opening has an inwardly extending ledge 30 terminating in a cylindrical flange 31. A seal comprises a cylindrical wall 32 with a flange 33 which is seated upon the ledge 30, and a bottom portion 12a located within 20 the scoring 13a. In this case the walls 31 and 32 are fitted tightly together so that this member cannot be withdrawn after it has once been inserted. Such a type of initial tamper-proof closure is advantageous as it is possible to fill the 25 container through the opening in the wall 31 and then insert the plug in position. This plug cannot be separated from the exterior thereafter without damage to other parts of the structure providing the opening.

30 It is obvious that the invention is not limited to the particular forms shown, but that it may be employed in many ways within the scope of the appended claims.

35 Having thus described the invention, what I claim as new and desire to secure by Letters Patent is:

1. The combination with a container having a closure wall with means for providing a discharge opening, and a friction seat around said opening, and a device including a pouring spout member and a reclosure member connected fixedly together, each member having a portion cooperative with the friction seat and each operative as a grip for removing the other member from its cooperation with the friction seat, and a swinging bail pivotally mounted on the container and pivotally engaged with said device for guiding either of said member portions to said friction seat.

50 2. The combination with a container having a closure wall with means for providing a discharge opening, and a friction seat around said opening, and a device including a pouring spout member and a friction reclosure member connected fixedly together, each member having a portion frictionally cooperative with the friction seat and each operative as a thrust member for forcing

the other member into frictional engagement with said friction seat.

3. The combination with a container having a closure wall with means for providing a discharge opening, and a friction seat around said opening, and a device including a pouring spout member and a reclosure member connected fixedly together, each member having a portion cooperative with the friction seat and each operative as a grip for removing the other member from its cooperation with the friction seat, and a swinging ball pivotally mounted on the container and pivotally engaged with said device for guiding either of said member portions to said friction seat, said portions being spaced like distances from the pivot connection between the device and bail so that each is presented to the friction seat and so that the closure cap does not obstruct the spout.

4. The combination with a container having a closure wall with means for providing a discharge opening, and a friction seat around said opening, and a device including a pouring spout member and a reclosure member connected fixedly together and each having a substantially cylindrical portion cooperative with the friction seat, the spout member having a pouring lip leading from the cylindrical portion and a rear portion opposite the pouring lip, the reclosure member being located adjacent and secured to said rear portion.

5. The combination with a container having a closure wall with means for providing a discharge opening, and a friction seat around said opening, and a device including a pouring spout member and a reclosure member connected fixedly together and each having a substantially cylindrical portion cooperative with the friction seat, the spout member having a pouring lip leading from the cylindrical portion and a rear portion opposite the pouring lip, the reclosure member having a peripheral flange, and said rear portion being curled about said flange.

6. The combination with a container having a closure wall provided with a depressed portion forming a friction seat, the bottom of said depressed portion being scored so that the metal may be ruptured and a pouring opening formed, a device including a pouring spout member and a reclosure member, each having a substantially cylindrical portion adapted to engage the friction seat, the pouring spout member having a pouring lip, said reclosure member being connected to said pouring spout member at a point peripherally spaced from said pouring lip.
